STRAND TWISTING APPARATUS

Albert E. Winslow, Mystic, Conn., assignor to
 Atwood Machine Company, a corporation of
 Connecticut

Application October 29, 1943, Serial No. 508,132

6 Claims. (Cl. 57—58)

This invention relates to a device for the twisting or laying of strand material and more particularly to a device adapted to impart more than one turn of twist to one or more strands for each revolution of the flyer.

In such a device the package or packages from which the strand material is supplied do not partake of the revolution of the flyer. The strands are drawn from the supply package or packages in a manner to form a loop which is carried by the flyer around the package or packages. Assuming the supply package to be mounted on a stationary axis, two turns of twist are imparted for each revolution of the loop about the package. The manner in which the supply package support is held stationary while mounted upon a rotating spindle with the yarn looping about the supply package has been accomplished in various ways and it is the means by which this result is accomplished which is the feature of this invention.

One of the objects of this invention is to provide a simple and efficient manner of positively holding the supply package support stationary while being mounted upon the revolving spindle which rotates the strands about the package support.

Another object of this invention is to provide a positive drive through the flyer from a stationary frame to the supply package support so as to prevent slip between the driving parts.

Another object of this invention is to utilize centrifugal force which is developed by a rotation of the flyer for maintaining a driving connection between the flyer and the stationary part on the one hand and the creel or supply package support on the other.

Another object of this invention is to provide an arrangement so that the greater the spindle speed more positive will be the driving connection between the flyer and its operating parts.

Another object of the invention is to provide a limit in the outwardly movement of the driving connection so that when the connection is by means of gear teeth there will be no jamming of the teeth one with the other.

Another object of the invention is to provide a positive driving connection between the relatively rotatable parts.

With these and other objects in view, the invention consists of certain novel features of construction, as will be more fully described and particularly pointed out in the appended claims.

In the accompanying drawing:

Fig. 1 is a diagrammatic view illustrating the travel of the strand from the supply package to its take-up reel with the operating parts shown in section;

Fig. 2 is a sectional view on substantially line 2—2 of Fig. 1;

Fig. 3 is a section on substantially line 3—3 of Fig. 1;

Fig. 4 is a sectional view showing the flyer driving gears.

The invention illustrated in this application forms an alternative arrangement of a part of a larger machine which is shown in my co-pending application Serial No. 517,859. The supply packages are designated 10 from which the strands of material 11 lead into the hollow spindle then downwardly together and radially outwardly as at 12 and thence upwardly as at 13 to loop the strands upon themselves, which loop is revolved about the axis of the spindle so that two turns of twist or lay are placed into the strands for each single turn that the loop makes about the spindle. The upwardly extending run of the work 13 is then guided from the machine through the ring 14 and between feed rolls 15 and 16 and thence led as at 17 over pulley 18 and over suitable guides 19 and 20 to be packaged as at 21, the package being operated by a surface drive 22 as diagrammatically shown in Fig. 1.

The spindle 25 is rotatably mounted by means of ball bearing 26 in the bolster 27 and casing 28 which is carried by a stationary part 29 consisting of the framework of the machine in which it is mounted. The spindle is driven by a whirl 30 which is fixed to the spindle by means of the set screw 31. An arm 32 supports an annular toothed race 33 at one side which is also supported by the bolt 34 at the other side which race is concentric with the spindle.

A creel designated generally 35 has a hub portion 36 and a plate 37 extending outwardly therefrom upon which a plurality of rods 38 are carried for the support of packages 10 of strand material. Rods 40 also similarly supported extend adjacent the packages to serve as a guide about which this strand material 11 is led prior to entering the hollow spindle. This creel or supply package support 35 is rotatably mounted upon the spindle by means of ball bearings 41, 41' the lower of which 41' engages a shoulder 43 on the spindle. The lower portion of the creel 35 is flanged as at 44 which provides an inner annular toothed raceway 45 concentric with the spindle.

A flyer designated generally 48 is formed with a hub portion 47 fixedly mounted upon the spindle to rotate therewith while a plate 48 engages the upper end of this hub 47 and extends outwardly therefrom to support the reel or pulley 23 over which the strand material extends. A recess 49 is provided for the reception of the other guide pulley 24 which is mounted tangent to the hollow bore 39 of the spindle. Hub 47 is provided with pairs of guideways 50 and 51 (see Fig. 3) equally angularly related and in this

particular case there being shown three in number. These guideways each slidably mount a block 52 which is recessed for the reception of a spring 53 which bears upon the hub and forces the block outwardly. The block is heavy enough however to be thrown outwardly by centrifugal force as the flyer rotates.

In each block there is provided a bore 55 for the reception of a shaft 56 which is rotatably mounted in this bore as a bearing. At the lower end of the shaft 56 there is a gear 57 which engages the annular toothed race 33 while at the upper end of the shaft there is a gear 58 which engages the annular toothed race 45. Thus, as the flyer 46 rotates the gear 57 will be driven by its engagement with the annular toothed race 33 to turn the shaft 56. Turning the shaft 56 will turn the gear 58 which will in turn drive the creel by its engagement with the toothed race 45 in the opposite direction. The annular races 33 and 45 are the same in diameter and also the friction disks 56 and 58 are the same in diameter. Thus, the annular toothed race 45 will remain always in the same relation to the annular toothed race 33. The annular race 33 is on a stationary part and accordingly although rotation of the shaft 56 occurs the annular race 45 will maintain the creel stationary or in its same relative position to the stationary part 32, 33 and regardless of the speed of rotation of the flyer the supporting creel will remain stationary.

The friction caused by centrifugal force plus the action of spring 53 will be sufficient to provide driving connection.

At either side of the two raceways 33 and 45 there are smooth raceways 60 and 61. The gear members or drive members 57 and 58 are each provided with shrouds 62 and 63 (see Fig. 4) which extend out beyond the edges of the teeth of the gears 57 and 58 and will engage the annular smooth surfaces 60 and 61 so as to prevent the teeth of these gears from being forced outwardly by centrifugal force an amount to cause the jamming of the teeth. These shrouds thus limit the amount that the teeth may extend into one another so as to maintain them in their correct driving relationship with their pitch circles tangent.

By this arrangement a positive drive occurs between the flyer and the stationary support on the one hand and the floating creel mounted on the flyer on the other hand so that the creel will not creep or move relative to the stationary support.

I claim:

1. In a strand twisting device, a spindle, a supply package support with respect to which the spindle is rotatable, an annular toothed race on said support, a second annular toothed race stationary with respect to said spindle, a flyer carried by the spindle, a radially slidable block carried by the flyer to be thrown out by centrifugal force as rotation of the flyer occurs, a shaft rotatable in said block, pinions on said shaft to one engage one toothed race and the other engage the other toothed race, and means independent of centrifugal force yieldingly urging said pinions into engagement with said toothed races.

2. In a strand twisting device, a spindle, a supply package support with respect to which the spindle is rotatable, an annular toothed race on said support, an annular surface adjacent said race, a second annular toothed race stationary

with respect to said spindle, an annular surface adjacent said race, a flyer carried by the spindle, a radially slidable block carried by the flyer to be thrown out by centrifugal force as rotation of the flyer occurs, a shaft rotatable in said block, pinions on each said shaft to one engage one toothed race and the other engage the other toothed race, and means independent of centrifugal force yieldingly urging said pinions into engagement with said toothed races.

3. In a strand twisting device, a spindle, a supply package support with respect to which the spindle is rotatable, an annular toothed race on said support, an annular surface at either side of said race, a second annular toothed race stationary with respect to said spindle, an annular surface at either side of said race, a flyer carried by the spindle, a radially slidable block carried by the flyer to be thrown out by centrifugal force as rotation of the flyer occurs, a shaft rotatable in said block, pinions on said shaft to one engage one toothed race and the other engage the other toothed race, and a pair of shrouds carried by said shaft one at either side of said pinion to engage said annular surfaces and limit the meshing of said pinions and toothed races.

4. In a strand twisting device, a spindle, a supply package support with respect to which the spindle is rotatable, an annular toothed race on said support, a second annular toothed race stationary with respect to said spindle, a flyer carried by the spindle, a plurality of radially slidable blocks carried by the flyer to be thrown out by centrifugal force as rotation of the flyer occurs, a shaft rotatable in each said block, pinions on each said shaft to one engage one toothed race and the other engage the other toothed race, and means independent of centrifugal force yieldingly urging said pinions into engagement with said toothed races.

5. In a strand twisting device, a spindle, a supply package support with respect to which the spindle is rotatable, an annular toothed race on said support, an annular surface adjacent said race, a second annular toothed race stationary with respect to said spindle, an annular surface adjacent said race, a flyer carried by the spindle, a plurality of radially slidable blocks carried by the flyer to be thrown out by centrifugal force as rotation of the flyer occurs, a shaft rotatable in each said block, pinions on each said shaft to one engage one toothed race and the other engage the other toothed race, and shrouds carried by each said shaft one adjacent each pinion to engage said annular surfaces and limit the meshing of said pinions and toothed races.

6. In a strand twisting device, a spindle, a supply package support with respect to which the spindle is rotatable, an annular toothed race on said support, an annular surface at either side of said race, a second annular toothed race stationary with respect to said spindle, an annular surface at either side of said race, a flyer carried by the spindle, a plurality of radially slid able blocks carried by the flyer to be thrown out by centrifugal force as rotation of the flyer occurs, a shaft rotatable in each said block, pinions on each said shaft to one engage one toothed race and the other engage the other toothed race, and a pair of shrouds carried by each said shaft on either side of said pinion to engage said annular surfaces and limit the meshing of said pinions and toothed races.

ALBERT E. WINSLOW.
